UNITED STATES PATENT OFFICE.

CHARLES R. HARE, OF HARTFORD, CONNECTICUT, ASSIGNOR TO THE ARROW ELECTRIC COMPANY, OF HARTFORD, CONNECTICUT, A CORPORATION OF CONNECTICUT.

PULL-SOCKET.

1,094,206.

Specification of Letters Patent. Patented Apr. 21, 1914.

Application filed December 18, 1913. Serial No. 807,466.

To all whom it may concern:

Be it known that I, CHARLES R. HARE, a citizen of the United States of America, and residing at Hartford, in the county of Hartford and State of Connecticut, have invented a certain new and Improved Pull-Socket, of which the following is a specification.

My invention relates to pull sockets and particularly to the lining therefor, the object of my invention being to improve the usual insulating lining in the feature herein-after described.

In the accompanying drawing, Figure 1 is a dropped perspective of a pull socket in the lining of which my invention is embodied in one form; Fig. 2 is a side elevation of the socket, partially broken away; and Fig. 3 is a vertical section through the lining alone.

The pull socket here shown, comprises cap 10, shell 11 and socket body 12 carrying screw shell terminal 13 and switch operating pull chain 14. The latter emerges from the casing through a chain bell 15 the base 16 of which is here shown mounted on the socket body, but it is to be understood that the invention is equally applicable to pull sockets in which the chain bell is mounted on the shell 11 as has been common practice until recently. An insulating lining 17 is generally provided within the shell to insulate the terminal 13 therefrom and to prevent accidental contact between the shell and any of the electrically alive parts on the socket body. This lining is provided with a slot 18 which embraces the base of the chain bell 15.

In pull sockets of the construction illustrated, the slot 18 engages each side of the base 16 of the chain bell 15. As a result of this arrangement it not infrequently happens that the inner edge of the lining projects beyond the inner edge of the base 16 of the bell and lies in the path of the chain 14 as it moves back and forth on the actuation of the switch. As a result, a certain amount of friction is caused even on the outward pull of the chain, while it not infrequently happens that the return of the chain under

the influence of the switch spring, is prevented through the engagement of the edge of the lining by a ball of the chain. To obviate this difficulty I have provided a clearance for the chain by bumping the lining outward adjacent the slot 18 at the point 19 which registers with the chain in the assembled position of the parts. While this clearance may be effected in various other ways, this particular method has the advantage of maintaining the insulation as perfect as heretofore. At the same time it adds to the security of the latching engagement between the shell and cap, since it presses outward against the portion of the shell in which the latching elements 20 are arranged and thus aids the spring of the metal in maintaining the latching engagement tight.

It is obvious that the outward bumping of the lining at 19 maintains the edge of the lining at this point out of position to engage or obstruct the movement of the chain as it enters or returns through the bell.

I claim as my invention:

1. In a pull socket, a casing, a socket body within the same, a chain bell having a base mounted on said body, an insulating lining surrounding said socket body and having a slot embracing said base of the chain bell, said lining being bumped outward adjacent said slot to afford a clearance for the pull chain, substantially as described.

2. In a pull socket, a casing, a socket body within the same, a pull chain carried by the latter, a lining interposed between said socket body and casing, said lining having a slot to permit the passage of said chain therethrough, and being outwardly bumped adjacent said slot to afford a clearance for the chain, substantially as described.

In testimony whereof I have signed my name to this specification, in the presence of two subscribing witnesses.

CHARLES R. HARE.
